UNITED STATES PATENT OFFICE.

GEORGE IRWIN PARK, OF TORONTO, ONTARIO, CANADA, ASSIGNOR, BY DIRECT AND MESNE ASSIGNMENTS, OF THREE-EIGHTEENTHS TO RUSSELL THORNTON COLLINS, TWO-NINTHS TO GEORGE SWANWICK, TWO-NINTHS TO CHARLES MONTAG, AND ONE-EIGHTEENTH TO FREDERICK W. GATES, ALL OF HAMILTON, ONTARIO, CANADA.

STOOKING ATTACHMENT FOR BINDERS.

1,356,308.

Specification of Letters Patent. Patented Oct. 19, 1920.

Application filed August 18, 1919. Serial No. 318,300.

To all whom it may concern:

Be it known that I, GEORGE IRWIN PARK, a subject of the King of Great Britain, residing at Toronto, in the county of York, Province of Ontario, Canada, have invented 5 certain new and useful Improvements in Stooking Attachments for Binders, of which the following is the specification.

My invention relates to improvements in 10 stooking attachments for binders, and the objects of the invention are:—firstly, to devise a stooker which will be more simple and which will more effectively form the sheaves of grain into a stook; secondly, to compress 15 the stook prior to its discharge to the stooking attachment; thirdly, to provide means for guiding the stook so as to keep it in the vertical position and also prevent it from falling over at the moment of impact with 20 the ground; and fourthly, to provide means for lowering the stook nearer the ground prior to discharge, for rendering the liability of its upsetting less when it comes in contact with the ground.

25 My invention consists of a suitable frame secured to the main frame of the binder and provided with a suitable support wheel, a stooking attachment of cone frustum shape revolvably mounted on the said frame, the 30 smaller end of the cone of the stooker being toward the rear, suitable gearing connected to the main driving wheel for revolving the stooker from the horizontal position into the vertical position, said gearing being provided with a clutch for rendering the same 35 inoperative when required, means actuated by the gearing for opening and closing the door of the stooker to receive the sheaves of grain, means actuated by the said gearing 40 for compressing the stook, means for releasing the stook compressed by the aforesaid gearing and means for guiding the stook during discharge and preventing the upsetting of the same at the moment of impact 45 with the ground, all as hereinafter more particularly described and illustrated in the accompanying drawings in which:—

Figure 1 represents a plan view of stooking attachment constructed according to my 50 invention showing the same applied to the main frame of the binder, the details of the stooker being omitted for the sake of clearness.

Fig. 2 is a transverse vertical section of the same showing the binder knotter and 55 table in dotted lines.

Fig. 3 is a longitudinal vertical section through A—B (Fig. 1).

Fig. 4 is a plan view showing the stooker in the horizontal position with the door of 60 the same removed.

Fig. 5 is a side elevation showing the stooker in the horizontal position.

Fig. 6 is an enlarged plan view of the stooker showing the same in the horizontal 65 position and the door of the same open to receive the grain.

Fig. 7 is an enlarged elevation of the other side of the stooker, to that shown in 70 Fig. 5.

Fig. 8 is an enlarged view similar to Fig. 5 showing the stooker up-ended into the second or vertical position wherein the stook is compressed.

Fig. 9 is a similar view to Fig. 8 only 75 showing the stooker in the discharging position.

Fig. 10 is a cross-section of the stooker showing the compressor member in the initial position, the stooker then being horizontal.

Fig. 11 is a cross-section of the stooker showing the compressor member in the second or compressed position, the dotted lines indicating the said compressor member in 85 the discharging position wherein it moves inwardly to guide the stook on the opening of the gates, the stooker then being in the vertical position.

Fig. 12 is a detail showing the rack for 90 opening the stooker door.

Fig. 13 is an enlarged longitudinal vertical section on the line X—Y (Fig. 1) showing the system of gearing for actuating the stooker from the main driving wheel of 95 the binder, the gear being in such position that the stooker will be up-ended corresponding to the position of the same in Fig. 8.

Fig. 14 is a similar view to Fig. 13 showing the gearing in the final position *i. e.* the position in which the stook is discharged corresponds to the position of the same illustrated in Fig. 9.

Like characters of reference indicate corresponding parts in the different views.

1 is the main frame of the binder, and 2 is the main driving wheel. 3 is a stoker supporting frame provided with a supporting wheel 4 and having the semi-circular 5 portion 5 so designed to prevent interference with the stoker.

6 is the stoker, cone frustum in shape, and provided with strengthening webs or bars 7. 8 are semi-circular frames forming 10 the end members of the compressor and to which the compressor portion 9 is rigidly secured, and 10 is the door of the stoker secured to the rod 11 which is revolubly mounted between the two frames 8. The 15 compressor portion 9, and the door 10 form the compressor member, the same being semi-circular in cross-section and half cone frustum in shape. 12 is the knotted table suitably mounted on the supports 13 connected to the main frame 1. 14 is the knotter 20 ter.

15 are cranks mounted in bearings 16 on the inclined faces 28 of the frame 3. 17 is a crank, the ends of which are mounted in 25 suitable bearings 18 on the frame 3. 19 is the cross shaft carrying a sprocket wheel 20 and also the portion 21 of a dog clutch, the other portion 22 being mounted on the inner end of the crank 17. 23 is a second 30 crank mounted in suitable bearings 24 and 25 on the frame 3 and the subsidiary frame 26 respectively. The outer end of the crank 23 extends through the bearing 24 and is mounted in the bearing 27 on the inclined 35 face 28 of the frame 3, said outer end carrying the gear wheel 29 designed to mesh with the gear wheel 30 on the cross shaft 31, said cross shaft being mounted in suitable bearings 32 and 33 on the inner inclined face 40 28, of the frame 3, and the frame 26 respectively. 34 is a quarter cut gear mounted on the same shaft 31 and adapted to mesh with a gear 35 having an outwardly extending sleeve 36, said sleeve and gear freely mounted 45 on the inner end 37 of the inner crank 15, said inner end 37 extending to the bearing 39 on the frame 3. The sleeve 36 extends through the bearing 16 and carries the arm 40 rigidly fixed to the end thereof which 50 extends through the bracket 41 on the inner side of the inner web 7. 42 is a gear keyed to the inner end of the crank 37 and adapted to mesh with the idler 43 revolubly mounted on the stud shaft 44 secured to the main 55 frame 3. This idler gear 43 in turn meshes with the three quarter gear 45 keyed to the cross shaft 31. 46 is a connecting rod connecting the two cranks 17 and 23 together. 47 is a sprocket wheel mounted on the main 60 driving shaft 48, and 49 is a chain connecting the two sprocket wheels 20 and 47 together.

The frames 8 of the compressor member carry the racks 50 and 51. 52 is a bevel gear 65 keyed to the outer end of the inner crank

15, said bevel gear having a spur gear 53 formed integrally therewith. The bevel gear 52 meshes with the bevel gear 54 keyed to one end of the shaft 55 which is mounted in bearings 56 on the upper face of the inner web 7. The other end of the shaft 55 carries the gear 57 which meshes with the rack 51. 58 is a shaft mounted in bearings 59 on the upper face of the inner web 7 and carrying at one end the gear 60 which 70 meshes with the gear 57, the other end of the shaft 58 being provided with a gear 61 which meshes with an idler gear 62 mounted in suitable bearings 63 on the inner web 7. The idler gear 62 in turn meshes with the 80 rack 50.

The gear 53 meshes with the rack 64 having the teeth 65, such rack being mounted in a suitable slide 66 on the outer face of the inner web 7. 67 is a lug on the top of 85 the rack 64 designed to engage the lug 68 on the rod 11 for opening the door. 69 is a wedge-shaped protuberance on the door 10 adapted to engage the outer face of the rack 64 for closing the door. 70 is a gear 90 mounted on the inner end of the outer crank 15 and adapted to engage the rack 71 mounted on the compressor portion 9. The rack extends through the aperture 72 in the stoker casing 73.

74 are the gates of the stoker mounted in suitable bearings 95 secured to the lower face of the inner and outer webs 7, the gates 74 being provided with curved depending tines 75. 76 is a shaft extending across the 100 top of the stoker 6 and revolubly mounted in the bearings 77 secured to the same. The shaft 76 is provided with crank shaped ends 97. 78 is a connecting rod connecting the cranks 97 with the cranks 15. 79 are eccentric 105 pivoted to the webs 7 by the brackets 80. 81 are studs on the eccentric portions, and 82 are portions hinged to the eccentric portions 79 and provided with notches 83 adapted to engage the studs 81. 84 are L-shaped links pivotally connected at one end to the hinged portions 82 and hinged centrally to the lower face of the webs 7 the other ends of such links being turned in so as to engage the slides 85 secured to the 110 tines 75. 86 are rods each pivoted at one end to the corresponding eccentric portion 79 and provided at the other end with a slot 87 in which the end of the corresponding crank 97 is designed to reciprocate. 115 The operation of the device is as follows:—

As the binder moves forward in the direction indicated by the arrows in Fig. 3, the sprocket wheels 47 and 20 are revolved and on the clutch portions 21 and 22 being 125 thrown into engagement, the crank 17 is revolved to the position shown in Fig. 13. As the crank 23 is connected to the crank 17 by the connecting rod 46, the crank 23 is revolved into the position shown in Fig. 130

13. Thus the gear 29 is turned, also the gear 30 meshing therewith. During this part of the operation the quarter gear 34 meshes with the gear 35 which is connected to the sleeve 36 and rotates the arm 40 about the crank end 37, thus turning the stooker 6 to a vertical position.

10 While this is being done the blank portion of the three-quarter cut gear 45 is opposite to the idler gear 43, so that the shaft 37 and with it the cranks 15 remain stationary. It will thus be seen that while the cranks 15 remain stationary, they change in position relatively to the stooker. In 15 other words, the stooker is revolved about the cranks 15. This operation causes relative rotation between the gear 52, and the rack 64 which meshes therewith thus raising the latter. Thus the rack 64 bears 20 against the wedge-shaped protuberance 69 causing the door to shut. While the stooker is revolved into the vertical position, bevel gear 52 revolves the gear 54, revolving the shaft 55 and the gear 57 thus lowering the 25 rack 51 and the gears 60, 61 and 62 are revolved, the latter lowering the racks 50. This achieves the compressing of the stook.

30 In the further rotation of the crank 17 in the position shown in Fig. 14, the crank 23 is further revolved to the position shown in this figure of the drawings and during this part of the operation the gear 45 is thrown into mesh. This gear 45 meshes with the idler gear 43 which in turn meshes with the gear 42, on the inner end 37 of the inner crank 15. This rotates the cranks 15 and lowers the stooker into the final position. During the above mentioned operation the compressor member is further compressed to the position shown in the dotted lines in Fig. 11. The door 10 is held shut during the operation by the rack 64 continuing to bear against the wedge shaped protuberance 69, as shown in dotted lines 40 in Fig. 11. This is done by the revolving of the cranks 15 which on the inner side rotate the gears 52, 54 and the remaining gears actuating the racks 50 and 51, and on the other side by the gear 70, actuating the rack 71. Simultaneously with this operation, the cranks 97 of the shaft 76 are revolved into the position shown in Fig. 9, through the medium of the connecting rods 78. This actuates the slotted rods 86 45 and causes the eccentric portions 79 to open from the hinged portions 82, causing the raising of such hinged portions and the consequent turning of the L-shaped links 84 from the position shown in Fig. 8 to the 50 position in Fig. 9. As these links bear against the slides 85 on the tines 75 the latter are caused to open about their bearings 95 and the stook is released.

60 It will be seen from the observation of Figs. 3, 13 and 14 that the further revolution

65 of the crank 17 from the position shown in Fig. 14 will cause the crank 23 and its connected gear 29 to be rotated in the reverse direction and thus the reversed operation will take place as described. The 70 compressor member will first be expanded into the position shown in Fig. 11 and on further rotation of the crank 17 the stook will be restored to the horizontal position and the compressor member then expands 75 to the position shown in Fig. 10. When this occurs the rack 64 will be turned down by the gear 53 and the lug 67 will engage the lug 68 on the rod 11, thus turning the door 10, which is secured to such rod, into 80 the open position indicated in Fig. 10. Consequently the stooker will now be in the initial position to receive further sheaves of grain for forming another stook. Concurrently, with restoring the stooker to the 85 initial position, the cranks 97 of the shaft 76 will be rotated in the opposite direction through the medium of the connecting rods 78, this will cause the slotted rods 86 to be actuated in the reverse direction and close 90 the eccentric portions 79 down on to the hinged portions 82 until the studs 81 engage the notches 83 on these hinge portions, consequently locking the eccentrics. This will 95 lower the hinge portions 82 rotating the links 84 about their bearings and consequently move them back into the position shown in Fig. 8, which will cause the gates 74 to close. This is, of course, done before the stooker is turned into the horizontal position. The turning into the horizontal position merely effects a further expansion of the compressor member and the opening of the door 10 to receive a fresh supply of 100 sheaves. It will also be observed that immediately prior to restoring the stooker to the horizontal position the cranks 15 will be revolved so as to raise the stooker to the initial position shown in Fig. 8.

105 From the above description it will be seen that the particular construction of my device will possess the advantages of being simple and positive in operation and, moreover, will compress the stook and prevent the same from being upset on its discharge. This is effected by the further compressing of the compressor member when the gates of the stook are being opened as is clearly shown in Fig. 11. On the stook coming in contact with the ground the tendency is, of 110 course, for the top to fall over in the direction in which the binder is proceeding. The further compression of the compressor member has a tendency to restore the stooker to the vertical position before the same ceases to have contact with the stook.

115 Many modifications may of course be made in my invention without departing from the spirit of the same or the scope of the claims. For instance, the system of gearing for 120

operating the stooker might readily be changed as desired to suit the requirements of different types of binders.

What I claim as my invention is:—

- 5 1. In a stooking attachment for binders, a stooker casing, gates hinged to the casing, a compressor member within the casing comprising a solid portion and a door, said door hingedly connected to the compressor member and means for moving the compressor member inwardly rectilinearly for compressing the stook against the gates prior to its discharge from the stooker. 70
- 10 2. In a stooking attachment for binders, a stooker casing, gates hinged to the casing, a compressor member comprising a solid portion and a door, means for moving the compressor member inwardly a certain extent for compressing the stook against the gates prior to its discharge from the stooker, means for opening the gates and means for moving the compressor member inwardly a further extent upon the opening of the gates. 75
- 15 3. In a stooking attachment for binders, a stooker casing, gates hinged to the casing, said gates constructed of substantially semi-truncated cone shape, a compressor member of substantially semi-truncated cone shape within the casing comprising a solid portion and a door, said door hingedly connected to the compressor member and means for moving the compressor member inwardly rectilinearly a certain extent for compressing the sheaves of grain against the gates, and forming them into a stook of substantially truncated cone shape. 80
- 20 4. In a stooking attachment for binders, a stooker casing of substantially semi-truncated cone shape, gates hinged to the casing, said gates constructed of substantially semi-truncated cone shape, a compressor member of substantially semi-truncated cone shape within the casing comprising a solid portion and a door, said door hingedly connected to the compressor member and means for moving the compressor member inwardly rectilinearly a certain extent for compressing the sheaves of grain against the gates, and forming them into a stook of substantially truncated cone shape. 85
- 25 5. In a stooking attachment for binders, a stooker casing, gates hinged to the casing, said gates constructed of substantially semi-truncated cone shape, a compressor member of substantially semi-truncated cone shape within the casing comprising a solid portion and a door, said door hingedly connected to the compressor member and means for moving the compressor member inwardly rectilinearly a certain extent for compressing the sheaves of grain against the gates, and forming them into a stook of substantially truncated cone shape. 90
- 30 6. In a stooking attachment for binders, a stooker casing having a suitable aperture, a compressor portion, a door, said compressor portion and door constituting a compressor member, said compressor member situated within the stooker casing, the door of the compressor member registering with the aperture in the casing, said stooker casing receiving the sheaves of grain in a horizontal position and means for upending the stooker casing into a vertical position. 95
- 35 7. In a stooking attachment for binders, a stooker casing, having a suitable aperture, a compressor portion, a door, said compressor portion and door constituting a compressor member, said compressor member situated within the stooker casing, the door of the compressor member registering with the aperture in the casing, said stooker casing receiving the sheaves of grain in a horizontal position and means for upending the stooker casing into a vertical position. 100
- 40 8. In a stooking attachment for binders, a stooker casing, having a suitable aperture, a compressor portion, a door, said compressor portion and door constituting a compressor member, said compressor member situated within the stooker casing, the door of the compressor member registering with the aperture in the casing, said stooker casing receiving the sheaves of grain in a horizontal position, means for upending the stooker casing into a vertical position, and means for lowering the stooker casing nearer the ground. 105
- 45 9. In a stooking attachment for binders, a stooker casing having a suitable aperture, a compressor portion, a door, said compressor portion and door constituting a compressor member, said compressor member situated within the stooker casing, the door of the compressor member registering with the aperture in the casing, said stooker casing receiving the sheaves of grain in a horizontal position, means for upending the stooker casing into a vertical position, means for lowering the stooker casing nearer the ground, and means for moving the compressor member inwardly for compressing the stook. 110
- 50 10. In a stooking attachment for binders, a stooker casing having a suitable aperture, a compressor portion, a door, said compressor portion and door constituting a compressor member, the door of the compressor member registering with the aperture in the casing, said stooker casing receiving the sheaves of grain in a horizontal position, means for upending the stooker casing in a vertical position, means for lowering the stooker casing nearer the ground, means for moving the compressor member inwardly 115
- 55 65 6. In a stooking attachment for binders, a stooker casing, gates hinged to the casing, said gates constructed of substantially semi-truncated cone shape, a compressor member of substantially semi-truncated cone shape comprising a solid portion and a door, means for moving the compressor member inwardly a certain extent for compressing the sheaves of grain against the gates, and forming them into a stook of substantially truncated cone shape. 120
- 60 65 7. In a stooking attachment for binders, a stooker casing, gates hinged to the casing, said gates constructed of substantially semi-truncated cone shape, a compressor member of substantially semi-truncated cone shape comprising a solid portion and a door, means for opening the gates and means for moving the compressor member inwardly a further extent upon the opening of the gates. 125
- 65 8. In a stooking attachment for binders, a stooker casing having a suitable aperture, a compressor portion, a door, said compressor portion and door constituting a compressor member, the door of the compressor member registering with the aperture in the casing, said stooker casing receiving the sheaves of grain in a horizontal position, means for upending the stooker casing in a vertical position, means for lowering the stooker casing nearer the ground, means for moving the compressor member inwardly 130

for compressing the stook, and means for moving the compressor member inwardly a further extent upon the discharge of the stook for preventing the upsetting of the same on impact with the ground.

11. In a stooking attachment for binders, a stooker casing having a suitable aperture, a compressor portion, a door, said compressor portion and door constituting a compressor member, said compressor member situated within the stooker casing, the door of the compressor member registering with the aperture in the casing, said stooker casing receiving the sheaves of grain in a horizontal position, means for upending the stooker casing into a vertical position, and means for moving the compressor member inwardly for compressing the stook prior to its discharge from the stooker.

12. In a stooking attachment for binders, a stooker casing having a suitable aperture, a compressor portion, a door, said compressor portion and door constituting a compressor member, said compressor member situated within the stooker casing, the door of the compressor member registering with the aperture in the casing, said stooker casing receiving the sheaves of grain in a horizontal position, means for upending the stooker casing into a vertical position, means for moving the compressor member inwardly for compressing the stook prior to its discharge from the stooker, and means for moving the compressor member inwardly a further extent upon the discharge of the stook for preventing the upsetting of the same on impact with the ground.

13. In a stooking attachment for binders, a stooker casing having a suitable aperture, gates hinged to the bottom of the stooker casing, a compressor portion, a door, said compressor portion and door constituting a compressor member, said compressor member situated within the stooker casing, the door of the compressor member registering with the aperture in the casing, said stooker casing receiving the sheaves of grain in a horizontal position, means for upending the stooker casing into a vertical position, means for moving the compressor member inwardly for compressing the stook prior to discharge, and means for opening the gates.

14. In a stooking attachment for binders, a stooker casing having a suitable aperture, gates hinged to the bottom of the stooker casing, a compressor portion, a door, said compressor portion and door constituting a compressor member, said compressor member situated within the stooker casing, the door of the compressor member registering with the aperture in the casing, said stooker casing receiving the sheaves of grain in a horizontal position, means for upending the stooker casing into a vertical position, means for moving the compressor member inwardly for compressing the stook in the stooker prior to discharge.

wardly for compressing the stook prior to discharge, means for opening the gates, and means for moving the compressor member inwardly a further extent upon the opening of the gates.

70

15. In a stooking attachment for binders, a stooker casing having a suitable aperture, a compressor portion, a door, said compressor portion and door constituting a compressor member, said compressor member situated within the stooker casing, and the door of the compressor member registering with the aperture in the casing, said stooker casing receiving the sheaves of grain in a horizontal position, means for opening and closing the compressor member door, and means for upending the stooker casing into the vertical position.

16. In a stooking attachment for binders, a stooker casing having a suitable aperture, a compressor portion, frames for the compressor portion, a door hinged to the frames, said compressor portion and door constituting a compressor member, said compressor member situated within the stooker casing, racks secured to the frames of the compressor portion, gears meshing with said racks and secured to the stooker casing and means for actuating the gears.

17. In a stooking attachment for binders, the combination with the main frame and driving wheel of the binder revolubly mounted thereon, of a stooker casing having a suitable aperture, a compressor portion, a door, said compressor portion and door constituting a compressor member, said compressor member situated within the stooker casing, said stooker casing receiving the sheaves of grain in a horizontal position, and means actuated by the driving wheel for upending the stooker casing.

18. In a stooking attachment for binders, the combination with the main frame and driving wheel of the binder revolubly mounted thereon, of a stooker casing having a suitable aperture, a compressor portion, a door, said compressor portion and door constituting a compressor member, said compressor member situated within the stooker casing, said stooker casing receiving the sheaves of grain from the binder in a horizontal position, means actuated by the driving wheel for upending the stooker casing, and means actuated by the driving wheel for moving the compressor member inwardly for compressing the stook in the stooker prior to discharge.

19. In a stooking attachment for binders, the combination with the main frame and driving wheel of the binder revolubly mounted thereon, of a stooker casing having a suitable aperture, a compressor portion, a door, said compressor portion and door constituting a compressor member, said compressor member situated within the stooker

21. In a stooking attachment for binders, the combination with the main frame and driving wheel revolubly mounted thereon, of a stoker casing having a suitable aperture, gates hinged to the bottom of the stoker casing, a compressor portion, a door, said compressor portion and door constituting a compressor member, said compressor member situated within the casing, said stoker casing receiving the sheaves of grain from the binder in a horizontal position, means actuated by the binder driving wheel for upending the stoker casing into a vertical position, means actuated by the binder driving wheel for moving the compressor member inwardly for compressing the stook prior to its discharge, means actuated by the binder driving wheel for opening and closing the gates, and means actuated by the binder driving wheel for moving the compressor member inwardly a further extent upon the opening of the gates, for preventing the upsetting of the stook on impact with the ground.

22. In a stooking attachment for binders, the combination with the main frame of the binder and driving wheel revolubly mounted thereon, of a subsidiary frame secured to the main frame, a stoker casing, cranks rotatably mounting the said stoker casing on said frame, gates suitably hinged to the bottom of the stoker casing, eccentric hinged to said stoker casing, plates hinged to the said eccentric, means for rotating the said cranks from the binder driving wheel, means connected with the cranks and eccentric portions for actuating the latter, and means connected with the hinged plates and gates for opening and closing the gates upon the rotation of the aforesaid cranks.
23. In a stooking attachment for binders, 75 the combination with the main frame of the binder, and the driving wheel revolubly mounted thereon, of a subsidiary frame secured to the main frame, a stoker casing, cranks rotatably mounting the said stoker 80 casing on said frame, gates suitably hinged to the bottom of the stoker casing, eccentric hinged to said stoker casing, plates hinged to the said eccentric, means for normally locking the hinged plates to the eccentric, means for rotating the said cranks from the binder driving wheel, means connected with the cranks and eccentric for actuating the latter, and means connected with the hinged plates and gates for opening and closing the gates upon the rotation of the aforesaid cranks.
24. In a stooking attachment for binders, the combination with the main frame of the binder and the driving wheel revolubly mounted thereon, of a subsidiary frame secured to the main frame, a stoker casing, cranks rotatably mounting the said stoker 85 casing on said frame, gates suitably hinged to the bottom of the stoker casing, eccentric hinged to said stoker casing, plates hinged to the said eccentric, said hinged plates having suitable notches, studs on the faces of the eccentric normally engaging the notches in the hinged plates, means for 90 rotating the said cranks from the binder driving wheel, means connected with the cranks and eccentric for actuating the latter, and means connected with the hinged plates and gates for opening and closing the gates upon the rotation of the aforesaid cranks.
25. In a stooking attachment for binders, the combination with the main frame of the binder, and the driving wheel revolubly mounted thereon, of a subsidiary frame secured to the main frame, a stoker casing, cranks rotatably mounting the stoker casing on said frame, gates suitably hinged to the stoker casing, a shaft having cranked ends 100 rotatably mounted at the top of the stoker casing, eccentric hinged to the said stoker casing, plates hinged to the said eccentric, connecting rods journaled at one end to the eccentric, and having the other end slotted, 105 said cranked ends of the aforesaid shaft reciprocating in said slotted ends of the rods, means for rotating the cranks, and means

- connected with the hinged plates and gates for opening and closing the gates upon the rotation of the aforesaid cranks.
26. In a stooking attachment for binders, the combination with the main frame of the binder, and the driving wheel revolubly mounted thereon, of a subsidiary frame secured to the main frame, a stooker casing on said frame, cranks rotatably mounting the stooker casing on said frame, gates suitably hinged to the stooker casing, a shaft having cranked ends rotatably mounted at the top of the stooker casing, eccentrics hinged to the said stooker casing, portions hinged to the said eccentrics, said hinged plates having suitable notches, studs on the faces of the eccentrics normally engaging the notches in the hinged plates, connecting rods each journaled at one end to one of the eccentrics, and having the other end slotted, said cranked ends of the aforesaid shaft reciprocating in said slotted ends of the rods.
27. In a stooking attachment for binders, the combination with the main frame of a binder, and the driving wheel revolubly mounted thereon, of a subsidiary frame secured to the main frame, a stooker casing on said frame, gates suitably hinged to the stooker casing, a shaft having cranked ends rotatably mounted at the top of the stooker casing, eccentrics hinged to said stooker casing, plates hinged to the said eccentrics, connecting rods each journaled at one end to one of the eccentrics, and having the other end slotted, said cranked ends of the aforesaid shaft reciprocating in said slotted ends of the rods, means for rotating the cranks, slides on the gates, and L-shaped links having inwardly turned free ends engaging the slides, each of the L-shaped links hinged centrally to the stooker casing, and the other ends hinged to the hinged plates.
28. In a stooking attachment for binders, the combination with the main frame of the binder, and the driving wheel revolubly mounted thereon, of a subsidiary frame, a stooker casing, a compressor portion, a door, said compressor portion and door constituting a compressor member, frames for supporting the compressor portion, said door hinged between the frames, outer and inner cranks rotatably mounting the stooker casing on the subsidiary frame, gears on the inner and outer ends of the outer and inner cranks respectively, a rack secured to the compressor portion, the gear on the inner end of the outer crank meshing with the said rack, racks secured to the frames of the compressor portion, a rotatable shaft mounted in bearings in the stooker casing, a gear on the forward end of the shaft meshing with the aforesaid gear on the outer end of the inner crank, a gear on the rear end of the shaft, meshing with one of the racks secured to the compressor portion, a second rotatable shaft mounted in bearings on the stooker casing, a gear on its rear end meshing with the gear on the rear end of the other shaft, a gear on its forward end, an idler gear rotatably mounted on the stooker casing, and meshing with the aforesaid gear on the forward end of the second shaft and with the other rack on the compressor member frame, and means for rotating the cranks from the binder driving wheel.
29. In a stooking attachment for binders, the combination with the main frame of the binder and the driving wheel revolubly mounted thereon, of a subsidiary frame, a stooker casing, a compressor portion, a door, said compressor portion and door constituting a compressor member, frames for supporting the compressor portion, said door hinged between the frames, outer and inner cranks rotatably mounting the stooker casing on the subsidiary frame, gears on the inner and outer ends of the outer and inner cranks respectively, a rack secured to the compressor portions, the gear on the inner end of the outer crank meshing with the said rack, racks secured to the frames of the compressor portion, a rotatable shaft mounted in bearings in the stooker casing, a gear on the forward end of the shaft meshing with the aforesaid gear on the outer end of the inner crank, a gear on the rear end of the shaft meshing with one of the racks secured to the compressor portion frame, a second rotatable shaft mounted in bearings on the stooker casing, a gear on its rear end meshing with the gear on the rear end of the other shaft, a gear on its forward end, an idler gear rotatably mounted on the stooker casing and meshing with the aforesaid gear on the forward end of the second shaft and with the other rack on the compressor member frame, means on the inner crank for upending the stooker casing into a vertical position, and means for rotating the inner crank from the binder driving wheel.
30. In a stooking attachment for binders, the combination with the main frame of the binder and the driving wheel revolubly mounted thereon, of a subsidiary frame, a stooker casing, a compressor portion, a door, said compressor portion and door constituting a compressor member, frames for supporting the compressor portion, said door hinged between the frames, outer and inner cranks rotatably mounting the stooker casing on the subsidiary frame, gears on the inner and outer ends of the outer and inner cranks respectively, a rack secured to the compressor portion, the gear on the inner end of the outer crank meshing with the said rack, racks secured to the frames of the compressor portion, a rotatable shaft mounted in bearings in the stooker casing, a gear on the forward end of the shaft meshing with the aforesaid gear on the outer end of the inner crank, a gear on the rear end of the shaft, meshing with one of the racks secured to the compressor portion, a second rotatable shaft mounted in bearings on the stooker casing, a gear on its rear end meshing with the gear on the rear end of the other shaft, a gear on its forward end, an idler gear rotatably mounted on the stooker casing and meshing with the aforesaid gear on the forward end of the second shaft and with the other rack on the compressor member frame, means on the inner crank for upending the stooker casing into a vertical position, and means for rotating the inner crank from the binder driving wheel.

- inner crank, a gear on the rear end of the shaft, meshing with one of the racks secured to the compressor portion frame, a second rotatable shaft mounted in bearings in the 5 stooker casing, a gear on its rear end meshing with the gear on the rear end of the other shaft, a gear on its forward end, an idler gear rotatably mounted on the stooker casing and meshing with the aforesaid gear 10 on the forward end of the second shaft and with the other rack on the compressor member frame, a sleeve freely mounted on the inner crank, an arm on said sleeve, a bracket on the stooker casing, said sleeve extending 15 through said bracket, means for rotating said sleeve from the binder driving wheel, and means for rotating the inner crank from the binder driving wheel.
31. In a stooking attachment for binders, 20 the combination with the main frame of the binder and the driving wheel revolvably mounted thereon, of a subsidiary frame, a stooker casing, a compressor portion, a door, said compressor portion and door constituting 25 a compressor member, frames for supporting the compressor portion, said door hinged between the frames, outer and inner cranks rotatably mounting the stooker casing on the subsidiary frame, gears on the inner and outer ends of the outer and inner cranks respectively, a rack secured to the compressor portion, the gear on the inner 30 end of the outer crank meshing with the said rack, racks secured to the frames of the compressor portion, a rotatable shaft mounted in bearings in the stooker casing, a gear on the forward end of the shaft meshing with the aforesaid gear on the outer end of the inner crank, a gear on the rear end of the shaft meshing with one of the racks secured 35 to the compressor portion frame, a second rotatable shaft mounted in bearing on the stooker casing, a gear on its rear end meshing with the gear on the rear end of the other shaft, a gear on its forward end, an 40 idler gear rotatably mounted on the stooker casing and meshing with the aforesaid gear on the forward end of the second shaft and with the other rack on the compressor member frame, means for opening and closing 45 the door of the stooker member, and means for rotating the inner crank from the binder driving wheel.
32. In a stooking attachment for binders, 50 a stooker, a compressor member mounted within said stooker, means for moving the compressor member inwardly for compressing the stook prior to discharge, and means for moving the compressor member inwardly and rearwardly a further extent on 55 discharge of the stook for retarding the forward movement of the top of the discharged stook in its impact with the ground.

GEORGE IRWIN PARK.
